UNITED STATES PATENT OFFICE

2,191,087

MAGNETO GENERATOR

Walter J. Spengler, Sidney, N. Y., assignor to
 Bendix Aviation Corporation, South Bend, Ind.,
 a corporation of Delaware

Original application February 25, 1933, Serial No.
 658,614, now Patent No. 2,012,290, dated August
 27, 1935. Divided and this application June 20,
 1935, Serial No. 27,476

3 Claims. (Cl. 200—30)

The present invention relates to magneto generators and more particularly to circuit breaker mechanism for ignition magnetos.

The present application is a division of the co-pending application, Serial Number 658,614, filed February 25, 1933, now Patent 2,012,290, August 27, 1935.

It is an object of the present invention to provide novel and improved circuit breaker mechanism for ignition magnetos particularly adapted for high speed operation.

It is another object to provide such a device in which wear of the breaker parts is reduced to a minimum.

It is a further object to provide such a device embodying means for the efficient and continuous lubrication of the moving parts.

It is another object to provide such a device in which the timing and adjustment of the breaker mechanism is convenient and readily observable.

Further objects and advantages will be apparent to those skilled in this art from the following description taken in connection with the accompanying drawing in which:

Fig. 1 is a view of the breaker end of a magneto incorporating a preferred embodiment of the present invention, the cover of the breaker being removed;

Fig. 2 is a vertical section of a portion of said magneto taken substantially on the line 2—2 of Fig. 1; and

Fig. 3 is a rear view of the carrier element for the breaker mechanism showing particularly the adjustment limiting means.

Referring first to Fig. 1 of the drawing, there is illustrated a portion of a magneto having a frame or casing indicated generally by numeral 1 having a rotor shaft 11 journaled therein carrying a cam 46 rigidly mounted thereon by suitable means such as a key 47 and stud 48, said cam being arranged to extend outwardly from the frame of the magneto 1 a considerable distance. A breaker assembly is mounted for rotary adjustment in the end of the casing 1 in position to be actuated by the cam 46. This breaker assembly comprises a cup-shaped carrier 49 arranged to seat in a circular flange 51 on the end of the casing 1 and to be retained therein by means of an elastic hook member 52 (Fig. 1) swivelled inside the carrier member 49 and adapted to engage a pair of anchorages in the form of pins 53 fixed in the end of casing 1 and projecting through slots 54 in the bottom of the carrier 49.

A fixed contact 55 is adjustably mounted in the carrier 49 as by means of sliding bracket member 56 fixed to the carrier 49 by means of studs 57 insulated from said carrier but connected to a conducting plate 58 (Fig. 2) at the back 5 of said carrier.

A movable contact 59 (Fig. 1) is mounted on a spring contact arm 61 anchored at 62 to a bracket 63 fixed to the carrier 49 by means of studs 64. The arm 61 is normally tensioned so as to hold 10 the movable contact 59 against the fixed contact 55 with a suitable pressure and is preferably stiffened at and adjacent to its free end as by means of flanges 65 formed thereon in order to prevent harmonic vibrations of the arm. A cam follower 15 66 is mounted on a spring arm 67 also anchored at 62 to the bracket 63, in position to cooperate with the cam 46, and is provided with an extension 68 arranged to engage near its free end the breaker arm 61 to move contact 59 away from 20 contact 55 when the cam follower 66 is on a lobe of said cam. The spring arm 67 is tensioned to maintain the cam follower 66 in engagement with the cam 46 at all times, and means in the form of a hook-shaped element 69 is provided for limiting the inward motion of the follower. The primary purpose of thus limiting the inward motion of the cam follower 66 is to facilitate the assembly of the breaker unit on the frame 1, since it is merely necessary to slightly bevel the 25 end of the cam 46 as indicated at 71 to insure that the cam follower does not interfere with the assembly operation by abutting on the end of the cam.

It will be particularly noted that the common 35 anchorage of the breaker arm 61 and the cam follower 66 at 62 prevents any sliding action taking place between the portion 68 of the cam follower 66 and said spring arm during the actuation of the spring arm by the cam follower. 40 This prevents wear at this point and correspondingly increases the life of the parts.

Means are provided for insuring efficient and continuous lubrication of the bearing surfaces of the cam 46 and cam follower 66 in the form of 45 an oil wick 72 fixed to the back of the cam follower 66 as by means of the rivets 73 which hold the cam follower on the spring arm 61, suitable spacing thimbles 74 around the rivets where they traverse the wick 72 being provided to prevent 50 undue compression of the wick at these points. The cam follower 66 is provided with an opening 75 therethrough adjacent its bearing surface, and the wick 72 is preferably compressed into the space at the rear of this opening so as to furnish 55

a supply of lubricant through said opening. The wick may if desired be extended as indicated at 16 to the bottom portion of the carrier 49 in order to pick up lubricant therefrom.

5 The fixed contact 55 is readily adjustable longitudinally by loosening the studs 57 and placing an instrument such as a screw driver with its point in one or the other of the depressions 77 or 78 in the carrier 49 adjacent the ends of the 10 bracket 56, and using such instrument as a lever to slide the bracket. Adjustment of the contact 55 axially of the rotor in order to line it up with the contact 59 may be effected by the use of shims beneath the bracket 63. The contact 59 is adjustable laterally with respect to the contact 55 15 to secure accurate alinement thereof by forming the opening for one of the studs 64 in the bracket 63 larger than necessary so that the bracket may pivot around the other stud 64 to secure such adjustment.

It will be noted that the cam 46 and contacts 55 and 59 all extend axially beyond the carrier 49 whereby observation and adjustment of the contacts when the magneto is mounted in a 25 confined position are greatly facilitated.

25 A suitable cover 79 (Fig. 2) is provided for sealing the breaker mechanism, and is preferably attached to the carrier 49 by readily detachable means such as the knurled studs 81 engaging in 30 threaded openings 80 in said carrier.

It will be noted that since the cam follower 66 35 always remains in engagement with the cam 46, the time of breaking of contacts 55 and 59 may be adjusted by sliding the bracket 56 back and forth irrespective of the maximum opening of said contacts or of any pitting thereof. In order to adjust the timing in accordance with the running conditions of the engine, an arm 97 (Fig. 1) is adjustably clamped as indicated at 98 to the carrier 49 and is adapted to be operated by a suitable linkage to rotate the carrier in order to advance or retard the time of the breaking of the contacts. This forms a secondary timing adjustment.

45 In the operation of this device, rotation of the rotor shaft 11 causes rotation of the cam 46 which moves the follower 66 to engage the movable contact arm 61 and cause the latter to operate contact 59 to open and close the primary circuit of the magneto. Adjustment of the timing of the spark during the operation of the magneto may be accomplished in the usual manner by bodily rotating the breaker mechanism by means of the arm 97 to suitably retard or advance the spark.

55 Although but one embodiment of the invention has been illustrated which comprises certain detailed structural features, it will be understood that the structural details are not necessarily exclusive and that changes may be made in the 60

dimensions and arrangements of the parts without departing from the spirit of the invention as defined in the claims appended hereto.

What is claimed is:

1. In apparatus of the class described, a cam 5 and a breaker assembly to be operated thereby including a cam follower, means for maintaining said follower continuously in engagement with said cam, a fixed contact, a movable contact, a spring arm carrying said movable contact and 10 maintaining it normally in engagement with the fixed contact, and an abutment on said cam follower movable by said cam into engagement with said spring arm to positively disengage the movable contact from the fixed contact, said cam 15 follower and spring arm being so mounted that their lateral movement in unison takes place without substantial relative translation.

2. In apparatus of the class described, a cam, 20 and a breaker assembly including a fixed contact, a breaker arm mounted with one end free to oscillate, a contact mounted on said arm adjacent the free end thereof and adapted to normally yieldingly engage said fixed contact, and cam follower means including resilient supporting means fixed at one end adjacent the fixed end of said breaker arm, an element carried by said supporting means and movable by said cam to engage and move said breaker arm to disengage said contacts, said element having an orifice 30 therethrough, said cam follower means and breaker arm being thus so mounted and arranged that substantially no relative movement occurs between the engaging portions thereof during the contact opening movement of the same, an oil soaked wick secured between said supporting means and element whereby oil is supplied from the wick to the surface of the cam and the bearing surface of the element through said orifice. 35

3. In apparatus of the class described, a cam 40 and a breaker assembly including a breaker arm having a resilient part adjacent at least one end thereof, means for fixedly mounting said end, a contact mounted on said arm adjacent the other end thereof for movement therewith, a fixed contact, said first-named contact being normally held in engagement with said fixed contact by said resilient part, cam follower means having a resilient portion fixed at substantially the same point as said breaker arm and a portion continuously held in engagement with said cam by said resilient portion, said cam engaging portion being movable by said cam to engage and actuate said breaker arm to disengage said contacts, said cam follower means and breaker arm being thus 50 so mounted and arranged that substantially no relative movement occurs between the engaging portions thereof during the contact opening movement of the same.

WALTER J. SPENGLER.
